Primary Examiner — Susan E Krakower*Assistant Examiner* — Jerry Shiuan-Hua Hsu*(74) Attorney, Agent, or Firm* — Saidman DesignLaw Group, LLC(57) **CLAIM**

The ornamental design for a side mirror for an automobile, as shown and described.

DESCRIPTION

FIG. 1 is a perspective view of a side mirror for an automobile showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines and the deenwhasized portions within illustrate portions of the side mirror for an automobile which form no part of the claimed design.

1 Claim, 7 Drawing Sheets(56)
